CLAIM

The ornamental design for the mowing apparatus, as shown and described.

DESCRIPTION

FIG. 1 is a front, right-side perspective view of the present mowing apparatus;

FIG. 2 is a top view of same;

FIG. 3 is a right-side view of the mowing apparatus of FIG. 1;

FIG. 4 is a left-side view of the mowing apparatus of FIG. 1;

FIG. 5 is a front view of same; and,

FIG. 6 is a rear view of same.

The broken lines in FIGS. 1-6 represent portions of the mowing apparatus that form no part of the claimed design.
